UNITED STATES PATENT OFFICE.

NATHAN J. GLASS, OF SAN FRANCISCO, CALIFORNIA.

ILLUMINATING DEVICE.

Application filed September 21, 1926. Serial No. 136,799.

This invention relates particularly to an improved form of illuminating device to be used for the projection of a beam of light.

An object of the invention is to provide 5 an illuminating device with a single prism mounted therein, and having a light generating means arranged relative to one side of the prism, to generate a beam of light which may be reflected outwardly in a selected direction.

A further object of the invention is to provide an illuminating device to be used as a headlight for vehicles, and other kindred uses, from which a beam of light of predetermined density and volume is reflected that does not possess nor is accompanied by the usual glare or blinding effect created by light reflecting devices of a conventional character.

20 A still further object of the invention is to provide a casing having an opening along one side thereof, said casing having a triangular prism therein, to reflect a beam of light from a suitable source of light supply, said prism being rotatably mounted in the casing, to adjust the angle of reflection of the light beam.

Other objects of the invention are to provide a device of the character described that 30 will be superior in point of simplicity, inexpensiveness of construction, positiveness of operation, and facility and convenience in use and general efficiency.

In this specification and the annexed 35 drawings, the invention is illustrated in the form considered to be the best, but it is to be understood that the invention is not limited to such form, because it may be embodied in other forms, and it is also to be understood that in and by the claims following the description, it is desired to cover the invention in whatsoever form it may be embodied.

In the accompanying one sheet of drawings,

Fig. 1 represents a cross section through an illuminating device constructed in accordance with my invention.

Fig. 2 is a longitudinal section taken 50 through Fig. 1 on the line 2—2.

Fig. 3 is a fragmentary section showing the method of mounting the light bulbs in the casing.

In detail the construction illustrated in 55 the drawings comprises a casing or housing 1, preferably circular in cross section, hav-

ing one end permanently closed by the end wall 2, and the opposite end closed by a removable cover 3. An elongated aperture 22 is provided lengthwise through the periphery of the casing 1, to provide an opening through which the beam of light, to be hereinafter described, may be reflected. A pair of socket members 4 and 5 are rotatably mounted in each of the opposite ends of the 60 interior of the casing 1, each socket member having flanges 6 struck out from the inside face thereof, to form a support for one of the opposite ends of the prism 7. The prism 7 has an over all length equal to that of the 70 space between the socket plates 4 and 5, whereby the ends of the prism may be snugly positioned in the socket flanges 6, to support the said prism in a relatively stationary position.

75 The socket plate 4 is provided with a stud 8 thereon that is rotatably journaled in the fixed end wall 2, while the opposite socket plate 5 is provided with a shaft 9 thereon that extends through a bearing 10 in the 80 removable cover 3. The end of the shaft 9 is threaded to receive a binding nut 11 thereon, by means of which the shaft 9 may be held in a non-rotating position relative to the cover 3. The prism 7 and its supporting 85 socket members 4 and 5 form a unitary structure so that the prism 7 and socket plates may be rotated within the casing 1 into any selected position and held in that position by tightening the binding nut 11 into 90 engagement with the cover 3 of the casing.

The prism 7 is provided with a polished front face 12 and a polished back face 13 and a reflecting surface 14. The intersection face 15 of the front and rear faces 12 95 and 13 is of a ground finish and parallels the reflecting surface 14. Along the back face 13 of the prism, I have arranged an open sided housing 16, which said housing 16 is connected at its opposite ends to the opposite 100 socket plates 4 and 5. The housing 16 has a sheath 17 slidably confined therein, in which a pair of light bulbs 18 and 19 respectively are mounted. The sheath 17 is adapted to extend through an opening in the 105 socket plate 5 whereby said sheath may be removed from its supporting housing 16 in order to fix or to adjust the light bulbs 18 and 19. The light bulbs 18 and 19 are connected by a suitable wire 20 to a source of 110 electrical supply (not shown).

The light generated by the bulbs 18 and

19 is projected from the bulbs and from the interior of the housing 16 through the polished back face 13 of the prism 7 and onto the reflecting surface 14 of said prism from 5 where the beam of light is reflected outwardly through the front face 12 of the prism. The aperture 22 in the casing 1 registers with the front face of the prism, and permits the beam of reflected light to be 10 projected outwardly from the casing 1. By rotating the prism in the casing, it is possible to adjust the angularity of the beam of reflected light. I have found that the beam of light reflected out from the prism 15 7 possesses none of the troublesome glare that is cast by illuminating devices depending for their intensity upon highly polished reflectors and various types of planar lenses. With my illuminating device, it is possible 20 for a person to look directly into the beam of light without being able to see the source from which the beam of light originates, and this eliminates the troublesome glare that is a source of annoyance in the majority of all conventional light diffusers.

Having thus described this invention, what I now claim and desire to secure by Letters Patent is:

1. An illuminating device comprised of a 30 prism having a reflecting surface and polished front and rear faces; and a light beam generator arranged adjacent the back face of the prism to cast a beam of light on the reflecting surface to be reflected out through the front face of the prism; and means to adjust the angularity of the prism and generator.

2. An illuminating device comprised of a 40 prism having a reflecting surface and polished front and rear faces, the intersection of the front and rear faces being ground to a non-reflecting surface parallel to the reflecting surface; and a light beam generator arranged adjacent the back face of the prism 45 to cast a beam of light on the reflecting surface to be reflected out through the front

face of the prism; and means to adjust the angularity of the prism and generator.

3. An illuminating device comprised of a 50 prism having a reflecting surface and polished front and rear faces; a light beam generator arranged adjacent the back face of the prism to cast a beam of light on the reflecting surface to be reflected out through the front face of the prism; a casing 55 enclosing the prism having an aperture therein registering with the front face of the prism; and means to rotate the prism in the casing to adjust the angularity of the front face of the prism.

4. An illuminating device comprised of a prism having a reflecting surface and polished front and rear faces, the intersection of the front and rear faces being ground to a non-reflecting surface; a light beam generator arranged adjacent the back face of the prism to cast a beam of light on the reflecting surface to be reflected out through the front face of the prism; a casing enclosing the prism having an aperture therein registering with the front face of the prism; and means to rotate the prism in the casing to 65 adjust the angularity of the front face of the prism.

5. In combination a casing having an aperture therein; rotatable socket members arranged at opposite ends of the interior of the casing; a prism having its opposite ends confined in the rotatable socket members, said prism having a reflecting surface and 70 polished front and rear faces; a light beam generator arranged adjacent the back face of the prism to cast a beam of light on the reflecting surface to be reflected out through the front face of the prism; and means to 75 hold the prism socket members in adjusted position within the casing.

In testimony whereof, I have hereunto set my hand at San Francisco, California, this 27 day of August, 1926.

NATHAN J. GLASS.
